DESIGN FOR A HAT

Alex Simbeck, San Francisco, Calif.

Application June 6, 1938, Serial No. 77,629

Term of patent 3½ years

To all whom it may concern:

Be it known that I, Alex Simbeck, a citizen of the United States of America, residing in the city and county of San Francisco and State of California, have invented a new, original, and ornamental Design for a Hat, of which the following is a specification, reference being had to the accompanying drawing, forming part thereof, in which:

The shaded portions indicate contrasting colors. The design shown on the band portion of the hat continues around the crown portion in the same manner as illustrated in Figure 2, but with the tower element and the rays omitted.

I claim:

The ornamental design for a hat, substantially as shown and described.

ALEX SIMBECK.
